UNITED STATES PATENT OFFICE.

JOHN R. MITCHELL, OF CHICAGO, ILLINOIS, ASSIGNOR TO WILLIAM H. MINER, OF CHAZY, NEW YORK.

ADJUSTABLE ROLLER SIDE BEARING.

1,290,286.

Specification of Letters Patent.

Patented Jan. 7, 1919.

Application filed August 20, 1917. Serial No. 187,214.

To all whom it may concern:

Be it known that I, JOHN R. MITCHELL, a citizen of the United States, residing at Chicago, in the county of Cook and State of Illinois, have invented a certain new and useful Improvement in Adjustable Roller Side Bearings, of which the following is a full, clear, concise, and exact description, reference being had to the accompanying drawings, forming a part of this specification.

This invention relates to improvements in adjustable roller side bearings.

An object of the invention is to provide a side bearing more particularly adapted for railway cars and which is of simple construction and adapted to tilt transversely of the axis of rotation of the roller.

Another and more specific object of the invention is to provide a side bearing of the type above indicated which is adjustable as to height.

In the drawing forming a part of this specification, Figure 1 is a vertical, sectional view, taken through portions of a body bolster, truck bolster and my improved side bearing associated therewith. Fig. 2 is a vertical, sectional view, taken substantially on the line 2—2 of Fig. 1. And Fig. 3 is an end elevation of one of the journal supporting blocks employed with my side bearing and illustrating the manner in which the adjustments for height are obtained.

In said drawing, 10 denotes the under wall of a body bolster of a railway car and 11 the upper wall of a corresponding truck bolster. As shown in the drawing, my improved side bearing is attached to the truck bolster.

The improved side bearing, as shown, comprises, broadly, a base casting B; an anti-friction bearing roller C; journal supporting blocks D—D; a journal E; and anti-friction rolls F—F.

The base casting B is of substantially rectangular formation and comprises a lower wall 12 riveted or otherwise suitably secured to the truck bolster; vertical upstanding end walls 13—13; vertically extending side walls 14—14 and suitable bracing flanges 15—15. The end walls 13 may be recessed, as indicated at 16, to prevent accumulation of dirt or other foreign matter within the bearing.

Each of the side walls 14—14 is provided with a substantially square recess 17 on its inner face, said recess providing a lower

horizontal shoulder 18, as most clearly appears in Fig. 2. Said recesses 17 are designed to accommodate the square blocks D—D, the blocks D—D having the tapered ends of the journal E secured therein, as clearly illustrated in Fig. 2. By referring to Fig. 3, it will be noted that the journal E is so mounted with respect to the blocks D that the center of the journal is located preferably 1 $\frac{1}{2}$ inches from the bottom of the block D, as illustrated in Fig. 3; 1 $\frac{1}{2}$ inches from the left hand edge; 1 $\frac{1}{2}$ inches from the right hand edge; and 1 $\frac{1}{2}$ inches from the top edge. With this arrangement, it is obvious that the height of the center of the journal E and consequently of the roller C carried thereby, can be varied from a minimum of 1 $\frac{1}{2}$ inches to a maximum of 1 $\frac{1}{2}$ inches by $\frac{1}{4}$ inch steps, depending upon the position in which the blocks D are inserted within the recesses 17. With this simple arrangement, I am enabled to provide a roller side bearing which is adjustable as to vertical height to compensate for variations or wear of the parts.

The roller C is hollow and on its interior the surface is crowned or convexed, as indicated at 19 in Fig. 2, said crowned surface 19 engaging and riding upon the circularly arranged series of rolls F, the latter in turn being carried by the journal E. With the crowned surface 19 above described, it is obvious that the roller C can tilt about an axis transversely to the axis of the journal E thereby accommodating the anti-friction roller to variations in the angle between the opposed surfaces of the body and truck bolsters and insuring a true full width bearing between the roller C and the adjacent bolster.

In order to limit the tilting movement of the roller, the side walls 20—20 thereof are provided with central openings 21—21 of substantially funnel shape, the blocks D being provided with inward truncated conical extensions 22 within the recesses 21. It is obvious that the side walls of the roller will engage said projections 22 to limit the tilting of the roller.

In assembling the roller C, journal E and rolls F, the rolls F are first placed within the roller C, after which the journal E is extended therethrough and thus the rolls F are positively prevented from escaping.

With the arrangement herein shown and described, the side bearing is adjustable to accommodate itself to variations in the angle

between the opposed bolster surfaces and also adjustable for variations in the vertical distance therebetween. The side bearing is composed of relatively few parts all of 5 which may be cheaply manufactured and readily assembled.

I claim:

1. In a device of the character described, the combination with a hollow anti-friction 10 roller, of a retaining member, a journal supported by said member, and anti-friction elements disposed around said journal and within the hollow roller, said elements and the inner surface of the roller having engagement permitting tilting of the roller in a direction transverse to its axis of rotation.
2. In a device of the character described, the combination with a retaining casting, of 15 a journal supported by said casting, a hollow roller through which said journal extends, said roller having its interior peripheral sur-

face crowned, and a series of anti-friction rolls interposed between said crowned surface and the journal.

3. In a device of the character described, 25 the combination with a retaining casting, of journal supporting blocks associated with said casting, a journal mounted in said blocks, a hollow roller having its interior face crowned, and anti-friction elements between said crowned face and the journal 30 whereby said roller is adapted to tilt transversely of its axis of rotation, the journal being off center with respect to said blocks whereby the height of the roller may be adjusted by changing the relation between the blocks and the base casting.

In witness that I claim the foregoing I have hereunto subscribed my name this 29th day of July 1917.

JOHN R. MITCHELL.
